MACHINE FOR ATTACHING ARTICLES TO
OTHER OBJECTS

Herbert A. Bickford, Warwick, R. I., assignor to
Boston Wire Stitcher Company, Portland,
Maine, a corporation of Maine

Application August 10, 1934, Serial No. 739,274

27 Claims. (Cl. 1—3)

This invention relates to stapling and wire-stitching machines and particularly to a device for attaching articles of commerce to display cards and other objects by means of staples or like fasteners and for similar purposes.

One object of the invention is to provide in a stapling or wire-stitching machine, means for locating the article in proper position on the object and attaching it thereto with a staple or similar fastener enclosing the article.

Another object of the invention is to provide means for holding the article and guiding the staple or like fastener into position to encompass its sides without causing undue pressure or strain to be exerted on the article itself.

Another object of the invention is to provide means for positioning the article and guiding the staple into place which, after the staple has been applied, is automatically displaced or removed from position to permit withdrawal of the card or other object to which the article is attached.

Another object of the invention is to provide a device of the type indicated which may be applied to use for fastening staples to milk bottle caps and similar articles to be used as a finger grip therefor.

Another object of the invention is to provide a device of the type indicated adaptable for use with either hand-operated or power-driven machines.

Another object of the invention is to provide a device of the type indicated which is simple in construction, proof against derangement or getting out of order, and efficient and durable in use for the purposes specified.

Further objects of the invention are set forth in the following specification which describes a preferred form of construction of the device, by way of example, as illustrated by the accompanying drawings. In the drawings:

Fig. 1 is a side elevation of a usual type of hand-stapling machine showing the present invention as applied therewith and illustrating the machine with its parts in position before the work is applied thereto;

Fig. 2 is a similar fragmentary view of the forepart of the stapling machine showing the work in place and the stapling head carried down into position for applying the staple;

Fig. 3 is a plan view of the article-positioning and staple-guiding means before the work is applied thereto;

Fig. 4 is a similar view showing the parts in position to hold the work and guide the staple;

Fig. 5 is a front view of the stapling machine showing the article-locating and staple-guiding means in position before the work is applied thereto;

Fig. 6 is a front elevation of the machine showing the stapling head depressed and the article-locating and staple-guiding means in position as the staple is applied to the work;

Fig. 7 is an enlarged part-sectional view of the fore part of the machine showing the work in place with the article held by the locating means and the staple applied to attach it to the object on which it is mounted;

Fig. 8 is a composite perspective view of the automatically-operated article-positioning and staple-guiding means of the machine;

Fig. 9 is a plan view of the front portion of the base of the machine showing a modified form of construction of the staple-guiding means embodying an anvil across which the staple is applied to adapt its legs to be clinched through a milk bottle cap or similar article;

Fig. 10 is a front elevation of the same;

Fig. 11 is a similar view in part section showing the stapling means as having been operated to drive the staple through the guides and across the anvil to clinch its legs through the article;

Fig. 12 is a perspective view illustrating the manner in which the articles are attached to a card or other object by the staples; and

Fig. 13 is a perspective view of a milk bottle cap showing a staple attached thereto to serve as a finger grip.

It is the present practice in merchandising small articles of commerce to attach them to display cards, easels or the like whereby they may be exhibited in attractive form on counters, in show cases or at other locations in stores and similar establishments. This method of display is used for many commodities such as toilet articles and packages of cosmetics or the like; for example, tubes of tooth paste, lipsticks, eyebrow pencils and small flasks of perfumery and other liquids packaged in similar form. In attaching such articles to a card or other object it is essential

that they be handled very carefully to avoid crushing the tubes, breaking the bottles or otherwise damaging their wrappers or containers; the present invention being particularly designed to retain the article in proper position on the object and to guide the staple in its application thereto without undue pressure liable to rupture the container or puncture the wrapper or other packaging means.

To this end the present invention provides a device having an opening proportioned to hold the article and to guide the staple into position for applying the same thereto. The device is particularly adapted for use with a hand-operated or power-driven stapling machine, the parts being held in position by the machine and being automatically displaced or removed from position to permit withdrawal of the card or other object to which the article is attached.

to enclose the article without pressure thereagainst and provided with guideways for directing the legs of the staple into place at the sides of the article without undue pressure thereon.

5 In addition, the article-locating and staple-guiding means is arranged to be automatically displaced at the completion of the stapling operation so that the object and its attached article may be conveniently withdrawn from the machine without interference by the holding and guiding means.

10 As before noted, the present invention is adapted for use with either power-driven or manually-operated machines and for the sake of simplification in the drawings it is herein illustrated as applied to a conventional type of hand-operated stapling machine for setting preformed staples.

15 Referring to the drawings, the illustrated machine comprises, in general, a base 2, adapted to rest on a bench, table or other support, and an arm 3 pivoted to the base at 4 to sustain the stapling mechanism in raised position above the work. A slideable plunger 5 at the rearward end of the arm 3 is urged downwardly by a pocketed spring 6 to adapt it to bear against the base 2, whereby to normally maintain the arm in raised position as shown in Fig. 1. The arm 3 is of hollow construction to provide a magazine for containing a supply of staples 8 to be successively fed to the stapling mechanism. As herein shown the staples 8 are straddled across a core 7 and fed forwardly within the magazine by means of a pusher 8 slideable therealong under the tension of a flat ribbon-like spring 9 attached to the pusher at 10. The forward end of the spring 9 is wound into a volute coil at 11 suitably maintained under tension to draw the pusher along the core 7.

20 The stapling mechanism is contained within a head 12 at the forward end of the arm 3 and comprises a staple-driver 15 in the form of a flat blade. The staple-driver 15 is formed with lateral fins or splines 16 slideable in vertical grooves or guideways 17 in the sides of the head 12. A plunger 18 carrying a hand-knob or presser 20 is connected to slide the driver 15, being normally held in raised position by a helical spring 21 to elevate the lower edge of the driver above the foremost staple in the series. The spring 21 is contained within the sides of the hollow plunger 18 with its upper end bearing against the under side of the knob or presser 20 and its lower extremity supported on a fixed abutment 22. The forward end of the staple-core 7 terminates at the guideways 17 for the driver 15. As the foremost staple in the series is fed off from the end of the core 7 it is received in the guideways 17 to be held suspended on a swiveled staple-supporter 25, shown by dotted lines in Figs. 1 and 2. The staple-supporter 25 is normally held in forward position as illustrated in the drawings by means of a spherically-ended plunger 26 operated by a helical spring 27 pocketed in a bore 28 in the head 12. As the driver 15 descends in the guideways 17 the staple 8 being driven thereby rides across the front of the supporter 25, thereby swinging the latter rearwardly to cause it to release the staple as the latter is applied to the work.

25 Set into the top of the base 2 at the forward end thereof is a clincher-block or anvil 24. Referring to Fig. 7, the top of the block 24 projects slightly above the top of the base 2 and is provided with the usual arcuately-shaped clincher-grooves 29 which receive the ends of the legs of the staple to bend them inwardly as they are driven through the work to clinch them against the under side

thereof. The parts of the machine thus far referred to are of known construction and therefore not shown and described more in detail.

30 The means for positioning the work and guiding the staple across the sides of the article to be attached are constructed and arranged as next described. Fastened to the top of the base 2 is a substantially flat spring-plate 30 secured in place at its rearward end by screws 31. The fore part of the spring-plate 30 is offset upwardly at 32 and extends at a slight angle to the top of the base 2. Supported on the forward end of the spring-plate 30 is a rigid member or guide-plate 33 which carries the positioning means for the article to be attached. As a preferable form of construction, the end of the spring 30 is rabbeted into a recess on the under side of the member 33 and secured thereto by screws 34 having their heads countersunk into the spring, thus providing a flush joint between the parts. The member or plate 33 is of bifurcated form as illustrated in Figs. 3 and 4, being provided with a slotted opening 35 at its forward end. The forward portions of the sides of the slot 35 are beveled or sharply inclined outwardly toward the top to form wedge-like cam-faces 36 designed for a purpose as later explained.

35 Received within the slot or opening 35 in the plate 33 are a pair of vertically and laterally movable fingers or dogs 40 constituting the means for positioning the article and guiding the staple in applying it to the work. Referring to Fig. 3, the dogs 40 are of complementary form and shape, each comprising a rectangular rearward portion 41 having straight sides adapted to abut the vertical sides of the rearward portions of the slot 35 when the dogs are assembled in parallel spaced relationship therein. The top of each rearward portion 41 of the dogs 40 is recessed at 42 to provide a slot for a bridge-member or top plate 43 resting across the top of the guide-plate 33. The bridge-plate 43 is secured fast to the top of the plate 33 by means of screws 44 and extends through the slots or recesses 42 in the dogs 40 to retain the latter in place in the slot 35 while adapting them for vertical movement therein. The facing sides of the dogs 40 are provided with pairs of holes 45 serving as pockets for receiving the ends of helical springs 46 held under compression to force the dogs apart.

40 The forward ends of the dogs 40 are provided with beveled sides 47 having an inclination corresponding to that of the beveled cam-faces 36 on the sides of the slot 35 in the guide-member 33. The inner faces 48 at the fore part of the dogs 40 are disposed in opposite parallel planes and formed at their forward ends with vertical grooves 50 which act as guideways for the staple as it is applied to the work. Outwardly beyond the grooves 50 the ends of the dogs are rounded off at 51. The vertical faces 48 on the fore part of the dogs 40 are offset laterally from the parallel faces on their rearward portions 41, thereby forming shoulders or abutments 52 which serve as stops to determine the longitudinal position of the article as it is inserted between the dogs prior to attaching it to the card or other object, indicated at C in Figs. 2, 7 and 12.

45 The method of operation of the complete stapling machine fitted with the device above described is as next explained. The machine has its parts normally positioned as illustrated in Fig. 1 with the stapling arm 3 held raised by the spring plunger 5 and the guide-plate 33 elevated above the top of the base 2 under the tension of the 75

spring-plate 30. The card C or other object to which the article is to be attached is placed across the top of the base 2 of the machine overlying and resting upon the clincher-block 24 and underlying the guide-plate 33, see Fig. 2. It will be understood that the machine is loaded with staples s straddling the core 7 in the magazine of the arm 3 and that the plunger 18 is held raised by its spring 21 with the lower edge of the driver 15 elevated above the foremost staple which has been fed into the grooves or guideways 17. The article to be attached, indicated by dash lines and designated *a* in Fig. 2 and illustrated in section in Fig. 7, is inserted into the opening between the sides 48 of the dogs 40 until its end brings up against the shoulders or abutments 52 on the dogs. While the article is being thus placed in position above the card C the dogs 40 are spread apart due to the pressure of the springs 46 extending therebetween. This action of the springs 46 causes the inclined faces 47 on the sides of the dogs 40 to cooperate with the cam-faces 36 on the sides of the slot 35 in the guide-plate 33 to lift the dogs slightly above the bottom of the plate 33; the extent of upward movement of the dogs being limited by the bridge-member 43 extending through the slots 42 in the rearward portions of the dogs. With the article *a* in place between the dogs 40 and resting on the card C the machine is ready for operation and the operator has only to press down on the knob 20 to actuate the various parts of the mechanism.

The first pressure of the hand on the knob 20 causes the arm 3 to be swung downwardly on its pivot 4, it being noted that the spring 21 is of greater tension than the spring 6 so that initially the plunger 18 is maintained in raised position. As the arm 3 swings downwardly the head 12 at its forward end strikes against the top of the opposed dogs 40 as indicated in Figs. 2 and 6, first causing the guide-plate 33 to be pressed down against the card C overlying the clincher-block 24 and thereafter forcing the two dogs bodily downward in the slot 35 of the guide-plate. As the dogs 40 are forced downwardly their inclined sides 47 coat with the cam-faces 36 on the sides of the slot 35 to draw the dogs toward each other, whereby they are brought into the position illustrated in Figs. 6 and 7 with their vertical sides 48 adjacent, but barely touching the article *a*. At this juncture the dogs 40 bring up against the top of the card C to prevent their further movement so as to avoid undue pressure against the article. In this way the dogs act to properly position the article on the card C and also to hold it in place for the stapling operation.

Continued pressure on the knob 20 causes the plunger 18 to be slid downwardly on the head 12 to carry the driver 15 downwardly therewith. As the driver 15 descends its lower edge impinges against the top of the foremost staple *s* in the series to slide the latter downwardly in the grooves or guideways 17. Meanwhile, the staple-supporter 25 maintains the staple in close association with the driver to prevent it from dropping out of the machine should the driver halt in its descent or from other cause. As the staple *s* is carried downwardly in the grooves 17 its legs enter the grooves 59 in the sides of the dogs 40 to guide them along the sides of the article without danger of their becoming misplaced or canted to puncture the wrapper or injure the contents of the package being attached to the card C. As the legs of the staple slide down in the grooves 59 their ends pierce through the card C and enter the grooves

29 in the clincher-block 24 whereby they are bent toward each other and clinched against the under side of the card in the usual manner as indicated in Fig. 7.

Upon completion of the staple-setting and clinching operation, pressure on the knob 20 is released and the plunger 18 will thereupon be slid upwardly on the head 12 to retract the staple-driver 15 into position for a subsequent operation. After the plunger 18 has been raised on the head 12 the stapling arm 3 will be swung upwardly under the force of its spring-plunger 5, thereby releasing the dogs 40. Immediately the dogs are released from the pressure of the stapling head 12 their springs 46 force them apart, thereby causing their beveled faces 47 to ride up the cam-faces 36. The dogs 40 are thus displaced away from the sides of the article *a* to release the legs of the staple *s* which has been applied to the work enclosing the sides of the article and clinched through the card C. The release of the dogs 40 allows the spring 30 to elevate the guide-plate 33 and thereby the card C is freed so that it may be drawn out of the machine with the article *a* attached thereto.

Usually, a plurality of articles are attached to the card C, being arranged in series therealong as illustrated in Fig. 12 of the drawings. With the present machine, after one article has been attached the card is simply drawn forward and shifted laterally to place it across the clincher-block in proper position for another article to be inserted between the dogs and attached in the manner as previously described. In this way any number of articles may be conveniently and expeditiously attached to a card or other object, the articles being lightly held in position during the stapling operation without undue pressure thereagainst to protect their wrappers and contents from damage. The hand-machine may be operated at a high rate of speed, while in other instances the present device may be applied to use with a power-driven stapler or stitching machine so that the operator is only required to place the article on the card whereafter the staple is applied to the work automatically.

Figs. 9 to 11 illustrate a modified form of construction of the present device for use in attaching staples to objects to project thereabove in the form of a loop; for example to adapt the staples to serve as finger-grips for milk bottle caps or the like. In this form of construction a rigid anvil 55 projects forwardly between the sides of the slot 35 in the guide-plate 33 to adapt it to support the staple while its legs are being clinched on the under side of the object; the anvil thus taking the place of the article held between the dogs in the operation of the first-described construction.

The anvil 55 is preferably formed integral with the plate 33, being constituted by a relatively-narrow rectangular bar extending forwardly from the rearward end of the slot 35 with its top depressed below the top of the plate as shown in Figs. 9 and 10. The forward end of the anvil 55 terminates short of the outer end of the slot 35 and has its corners chamfered at 56. As in the previously described construction, the sides of the slot 35 in the plate 33 are beveled or inclined outwardly toward the top, but in this case the bevels extend throughout substantially the whole length of the slot to provide continuous cam-faces 57.

The dogs 60, instead of being arranged to slide vertically within the slot 35, are pivotally mounted at their rearward ends to adapt their forward

ends to swing downwardly. The dogs 60 have beveled outer sides 61 and are cut away or chamfered on their facing sides parallel with the beveled faces 61, thereby providing flat portions through which extend pivot screws 63. The pivot screws 63 have shouldered bodies projecting through holes in the dogs 60 with their reduced ends screwed into the inclined sides of the slot 35, whereby to pivot the dogs on axes extending 10 at right-angles to the cam-faces 57. The inner ends of the dogs are cut away along their sides at 64 to provide a clearance at the sides of the anvil 55. At their forward ends the dogs 60 are provided with vertical guiding grooves 65 for the 15 staple, the grooves being disposed to align with the chamfered corners of the anvil 55. A flat, U-shaped spring 67 fastened to the top of the plate 33 by screws 68 has its legs 69 extending forwardly and curved downwardly to bear against 20 the rearward ends of the dogs 60 whereby to maintain their forward ends elevated as shown in Fig. 10.

With the last described form of construction the clincher-block 70 is preferably varied somewhat in structure from that used with the device as first described. Referring to Fig. 11, the arcuate grooves 71 in the block 70 are directed outwardly instead of toward each other so as to bend the legs of the staple outwardly, this variation in 25 the form of the clinch being in accordance with a usual practice.

With the last described form of construction of the device the milk bottle cap B or other object is placed across the top of the clincher-block 70 and the bottom of the stapling head 12 brought 30 down against the top of the dogs 60. The forward ends of the dogs are thus caused to rock downwardly from the position shown in Fig. 10 to that illustrated in Fig. 11 with their bottom faces resting against the top of the cap B or other object. Then as the staple-driver 15 is forced 35 downwardly in the stapling head 12 it will drive the staple through the guideways 65 in the dogs 60 until the head or crossbar of the staple 5 brings up against the top of the anvil 55. At this juncture the legs of the staple will have pierced 40 through the object B and entered the grooves 71 in the clincher-block 70 to be bent outwardly to clinch them against the under side of the object.

After the staple 5 has been clinched through the milk bottle cap B or other object the staple-driver 15 is retracted upwardly within the head 12 and the latter elevated above the work by the return movement of its arm 3. As soon as the 50 pressure on the forward ends of the dogs 60 has been released the legs 69 of the spring 67 operate to rock the dogs on their pivot screws 63 to elevate their forward ends to initial position as shown in Fig. 10. Upon the dogs being released and rocked upwardly their forward ends are spread apart to release the staple 5 from their grooves 65 so that the milk bottle cap B may be withdrawn to slide the staple off from the end of the anvil 55.

With the last described embodiment of the invention staples may be applied to various objects with the ends of their legs clinched through the work and their cross-bars standing in spaced relation thereabove. Staples applied in this manner are adapted to various and sundry uses besides that herein mentioned.

It will be observed from the foregoing that the present invention provides a novel and ingenious device for attaching articles of commerce to cards 75 and other objects or for setting staples in milk

bottle caps and other objects to project thereabove in the form of loops. The invention thus accomplishes the various objects mentioned in the preamble of the present specification besides being useful for other purposes. The device is extremely simple in construction, reliable in operation, and efficient for the purposes specified.

Various modifications other than that herein shown may be made in the structure and arrangement of the parts of the device without departing from the spirit or scope of the invention. Therefore, without limiting myself in this respect, I claim:

1. A machine for attaching articles to cards 15 and other objects comprising means movable to engage the article to position it on the object, and means acting at right-angles to the plane of movement of the positioning means for applying a fastener to attach the article to the object, said 20 positioning means acting to guide the fastener into place with respect to the article.

2. In a machine of the type indicated, the combination of a work-support, stapling mechanism arranged above said support, a plate 25 pivotally mounted on and overlying the work-support, and movable members carried by the plate and automatically operative on an article placed on the support to locate said article in register with the stapling mechanism. 30

3. In a machine of the type indicated, the combination of a work-support, stapling mechanism arranged in opposition to said support, guiding means disposed adjacent the support to overlie an object placed thereon and pivotally 35 mounted for movement toward and away from said support, positioning members slidably mounted on said guiding means for engaging an article to position it on the object, and means for automatically operating the guiding means 40 and positioning members previous to the stapling operation.

4. In a machine of the type indicated, the combination of a work-support, stapling mechanism arranged above said support, guiding means movable laterally with respect to the stapling mechanism, said guiding means being wholly disposed 45 between the stapling mechanism and work-support and mounted independently thereof, and means automatically operative during the operation of the stapling means to actuate the guiding means to position an article on the work-support to register it with the stapling mechanism. 50

5. In a machine of the type indicated, the combination of fastener-applying means, a work- 55 support, work-positioning means arranged wholly between the fastener-applying means and work-support, said work-positioning means comprising relatively movable members, and means for actuating the work-positioning means to close the relatively movable members against the sides of the work to position it in register with the fastener-applying means.

6. In a machine of the type indicated, the combination of a work-support, fastener-applying 65 means arranged above said support, a movable plate below the fastener-applying means adapted to rest against an object to hold it on the work-support, and means carried by the plate and automatically operative to move toward the sides 70 of an article placed on the object to locate the article in register with the stapling means.

7. In a machine of the type indicated, the combination of fastener-applying means, a work-support arranged adjacent the fastener-applying 75

means, guiding members for the work movable laterally of the work-support, grooves in said members for guiding the legs of a staple at the sides of the work, and means automatically operative to move said guiding members toward each other to position the staple-guiding grooves and work in register with the legs of the staple and the fastener-applying means.

8. In a machine of the type indicated, the combination of fastener-applying means, a work-support, guiding members movable laterally of the work-support, means for automatically moving said guiding members toward each other to position the work before the fastener is applied thereto, grooves in the guiding members for guiding the legs of a staple at the sides of the work, and means for separating the guiding members to release the legs of the staple and the work after the fastener has been applied thereto.

9. In a machine of the type indicated, the combination of fastener-applying means, a work-support, a plate arranged above said support to bear against the work placed thereon and having an opening therein, positioning members located in the opening in said plate and movable toward and away from each other, said members having grooves for guiding the legs of the staple, means to move said positioning members together to locate an article placed on the work and position the guiding grooves in register with the fastener-applying means, and means to separate said positioning members after the operation of the fastener-applying means to release the legs of the staple.

10. In a machine of the type indicated, the combination of a work-support, fastener-applying means adapted to move toward the work-support, pivotally mounted means located above the work-support and movable with the fastener-applying means into engagement with the work, and spaced laterally-movable members carried by the pivotally-mounted means and acting to locate an article in register with the fastener-applying means as the latter is moved toward the work-support.

11. In a machine of the type indicated, the combination of a work-support, fastener-applying means movable toward the work-support, means located between the fastener-applying means and the work-support and movable to engage the work to hold it in position, and a pair of cooperating movable members carried thereby and acting to position an article placed on the work to locate it in register with the fastener-applying means.

12. In a machine of the type indicated, the combination of a work-support, fastener-applying means movable toward the work-support, means normally maintained between the fastener-applying means and work-support and movable toward the latter with the fastener-applying means to engage the work, and means on the last-named means automatically movable toward each other during the movement of the fastener-applying means and movable away from each other upon the withdrawal of the fastener-applying means.

13. In a machine of the type indicated, the combination of a work-support, fastener-applying means movable toward the work-support, work-guiding means yieldingly sustained above the work-support and movable against the work held thereon, positioning members movable toward each other on the guiding means, means for automatically moving said members toward

each other prior to the operation of the fastener-applying means, and means for separating said positioning members after the operation of the fastener-applying means.

14. In a machine of the type indicated, the combination of a work-support, fastener-applying means movable toward the work-support, positioning members movable toward each other above the work-support during the operation of the fastener-applying means and provided with guideways for directing a fastener into the work, and means to separate said guiding members after the operation of the fastener-applying means to release the fastener.

15. In a machine of the type indicated, the combination of a work-support, a staple-driving means adjacent the work-support, a pair of work-engaging dogs arranged above the support and provided with spaced parallel guideways for a staple in register with the staple-driving means, means for moving said dogs toward each other prior to the driving of the staple, and means for separating said dogs after the staple has been applied to the work.

16. In a machine of the type indicated, the combination of a work-support, an anvil supported above the work-support, staple-driving means adjacent the work-support, and guiding means for the staple movable laterally toward the anvil before the operation of the staple-driving means and movable away from the anvil after the staple has been applied to the work.

17. In a machine of the type indicated, the combination of a work-support, guiding means overlying the work-support to engage against the work held thereon, staple-driving means arranged above the work-support, an anvil projecting above the work-support, said anvil being spaced from the work-support for the insertion of work therebetween, and guiding means for the staple automatically movable into position at the sides of the anvil to guide the legs of the staple as the latter is driven across the anvil.

18. In a machine of the type indicated, the combination of staple-driving means, a work-support, clincher-means on the work-support, a guide-plate yieldably supported above the work-support, a pair of dogs mounted to move toward each other on the guide-plate, and means operated from the staple-driving means to move said dogs to locate an article on the work placed above the work-support.

19. In a machine of the type indicated, the combination of a work-support, clincher-means on the work-support, fastener-applying means arranged above the work-support, a slotted guide-plate yieldingly sustained above the clincher means, dogs movable toward and away from each other in the slot of the guide-plate, and means for automatically moving the dogs toward each other prior to the operation of the staple-driving means and displacing them away from each other after the operation of the staple-applying means.

20. In a machine of the type indicated, the combination of a work-support, clincher-means on the work-support, staple-driving means movable toward the work-support, a guide-plate yieldingly sustained above the work-support to move toward the clincher-means, a pair of dogs movable toward each other on the guide-plate and formed with guideways for the staple, and means for automatically moving said dogs toward each other prior to the stapling operation and displacing them away from each other after the stapling operation.

21. In a machine of the type indicated, the combination of a work-support, clincher-means on the work-support, staple-driving means movable toward the work-support, a guide-member yieldingly sustained in spaced relation to the work-support to adapt it to move toward the latter to engage against the work, dogs movable toward and away from each other on the guide-member to locate an article on the work held thereby, and means automatically operative to move the dogs toward each other prior to the operation of the staple-driving means and to separate said dogs after the staple has been applied to the work.
22. In a machine of the type indicated, the combination of a work-support, clincher-means on the work-support, staple-driving means movable toward the work-support, a guide-member yieldingly maintained in spaced relation to the work-support to adapt it to move toward the latter, a pair of dogs movable toward and away from each other on the guide-member, and camming-means for moving said dogs toward each other with the movement of the staple-driving means.
23. In a machine of the type indicated, the combination of a work-support, stapling means movable toward the work-support, a guide-member formed with a slot with beveled faces at its sides, dogs held in said slot and provided with beveled sides engaging the beveled faces thereof, and resilient means for forcing the dogs apart, said dogs being engageable by the stapling-means to move them in the slot in the guide-member to cause the beveled sides thereof to force the dogs toward each other.
24. In a machine of the type indicated, the combination of a work-support, stapling mechanism arranged above said support, an element normally positioned above the support and below the stapling mechanism, positioning members car-
- ried by said element for engaging and positioning an article with respect to the work-support, and means for camming the positioning members toward and away from each other during the movement of said element respectively toward and away from the support.
25. In a machine of the type indicated, the combination of a work-support, stapling mechanism arranged above said support, an element normally positioned above the support to be moved by the stapling mechanism into engagement with the support, positioning members carried by said element and laterally movable with respect to the direction of movement of the element for positioning an article on the work-support, said positioning members being actuated by the stapling mechanism after the element is engaged with the support, and means for limiting the movement of the positioning members.
26. In a machine of the type indicated, the combination of a work-support, stapling mechanism movable toward the support, a guide-member having opposite beveled faces, and a pair of positioning members carried by the guide-member and having beveled faces cooperating with the beveled faces of said guide-member, said positioning members being engaged by the stapling mechanism to cause the cooperating beveled faces to move them toward each other to locate an article on the work-support.
27. In a machine of the type indicated, the combination of a support for an object, fastener-applying means arranged above said support, and positioning members mounted independently of the fastener-applying means and disposed below the latter and above the support, said members being operated automatically by the fastener-applying means to position an article on the object placed on the support in proper relation to the fastener-applying means.

30. 35. 40. HERBERT A. BICKFORD.
